PROCESS OF MULTICOLOR PRINTING.

No. 832,911.

Specification of Letters Patent.

Patented Oct. 9, 1906.

Application filed December 26, 1905. Serial No. 293,309.

To all whom it may concern:

Be it known that I, EMILE C. JESSURUN, a citizen of the United States, residing at Chicago, in the county of Cook and State of Illinois, have invented a certain new and useful 5 Process of Multicolor Printing, of which the following is a specification.

This invention relates to an improved process of multicolor printing; and it has for its 10 salient objects to provide a process in which great exactness of register in the superposed prints is not necessary and which accordingly is better adapted for newspaper-presswork and analogous presswork performed on machines not ordinarily capable of producing 15 great exactness of register; to provide a process in which the several steps are characterized by simplicity and the omission of manipulations requiring great skill or exactness; to 20 provide a process by means of which the detail lines and colors are made to stand out sharply and clearly independently of inaccuracy of register or color blendings, and in general to provide an improved process of 25 the character referred to.

The invention consists in the matters hereinafter described, and more particularly pointed out in the appended claims.

In carrying out the process I first make 30 or procure an outline-drawing of the subject, the lines of which are drawn in a color which will photograph sharply, preferably, of course, black. From this original I make a photographic negative plate of the desired size, and from the negative thus prepared I make a line or half-tone (preferably line) printing-plate by any usual photomechanical process. With the printing-plate thus prepared I make two prints, both on a suitable non-shrinkable surface—one in black or analogous dense color and the other in a lesser color, preferably blue or other color toward the violet end of the spectrum. One of these prints thus prepared—the black or dense-color print—serves as the object or original, from which is made a key-plate or a second line or half-tone printing-plate, and the other print in the lesser color is filled in or completed by hand with the set of colors (other 45 than the black) which appear in the finished multicolor print.

Referring to the drawings accompanying this description, Figure 1 represents the outline-sketch from which the key-plate is made,

and the same figure of course represents the 55 outline-sketch in the lesser color, which is subsequently filled in with the other colors. Fig. 2 represents the outline-print in the lesser color with the other colors filled in, these colors being indicated in accordance with the 60 conventional shading to designate colors—that is to say, in the figure of the lady the hat and belt are black, the face and hands orange, 65 waist blue, the dress red, and the bag held in the hand and the bow on the hat are green and purple, respectively.

It will of course be understood that any color or blending of colors may be used in preparing this picture or design precisely the same as though it were to be reproduced 70 by any of the known tri-color or four-color processes.

Having thus prepared the pair of complementary subject designs, I next proceed to prepare a set of printing-plates therefrom, 75 comprising one key-plate or line or half-tone printing-plate made from the outline design and three color-plates made from the color design and corresponding to the respective 80 colors.

In making this set of printing-plates I may make them by what is known as the "direct" process or by the indirect process, it being understood that in the direct process the photographic negative plates from which the 85 final printing-plates are made are exposed with the screen and filter both interposed between the subject and sensitized plate, whereas in the indirect process the color separation is effected by one exposure and the 90 screen image by another exposure and upon a different plate.

In making the three photonegatives corresponding to the three colors I proceed in precisely the usual way—namely, by making the exposure through suitable color-filters and making the successive negatives without disturbing either camera or subject—in order to secure exactness of register. These color-printing plates are so prepared as to have the usual half-tone lines or the alternative stipple tinting commonly known as the "metzograph-screen" effect. The fourth negative is made from the outline-drawing subject with precisely the same adjustment of the 100 camera and subject relatively to each other, and in order to avoid misregister I substitute 105 for the color-filter used in effecting the sepa-

ration of color in the color-negatives a colorless and transparent filter having the same refractive power as the color-filters. By so doing I secure a negative from which to 5 make the key-plate which will register exactly with the color-plates. From the set of four negatives thus produced I make the set of final printing-plates in any usual way, and from these printing-plates I print the picture 10 in the usual manner, except that the black or key plate impression is taken last.

I have found in practice that by omitting the detail lines from the color-printing plates and then adding these detail lines by means 15 of a key-plate, as described, I am able to produce a picture in which the detail appears sharply and clearly, and, what is of more importance, any reasonable amount of inaccuracy of register of the several plates is not 20 readily noticeable or, at least, not seriously objectionable.

It should be noted that the object of printing the outline-print, which is subsequently filled in to produce the colored subject, in a 25 blue or other color of low value or high light-reflecting power is of course to prevent these outline lines from reproducing prominently in the color-plates. Of course, if care be exercised, these lines might be more or less perfectly covered with the colors applied; but, 30 inasmuch as one of the main objects of the invention is to avoid the necessity of manual skill and accuracy, such suggested course would be disadvantageous.

35 In describing the process I have described the making of a preliminary printing-plate from which to prepare the outlines of the complementary subjects by the photomechanical process. Obviously these outline- 40 prints for the two complementary subjects might be made in any other suitable manner, so long as they are exact facsimiles and of the same size.

I claim as my invention—

45 1. The improvement in the art of making multicolor prints which consists in first preparing a pair of complementary subject designs, one a line-drawing and the other a color design adapted when the two are superposed to register so that they complement each other, next preparing a printing key-plate from the line-drawing and a set of printing color-plates from the color design, all adapted to register as to the design, 50 and then making the final print by successively printing, in superposed relation, the several colors from the corresponding color-plates and finishing with the impression from the key-plate.

60 2. The improvement in the art of making multicolor prints which consists in first pre-

paring a pair of complementary subject designs, one a line-drawing printed in a color of low light-reflecting power and the other a color design printed in a color of greater 65 light-reflecting power and adapted when the two are superposed to register so that they complement each other, next preparing a printing key-plate from the line-drawing and a set of printing color-plates from the color 70 design, all by a photomechanical process, and then making the final print by successively printing, in superposed relation, the several colors from the corresponding color-plates and finishing with the impression from the 75 key-plate.

3. The improvement in the art of making multicolor prints which consists in first preparing a pair of complementary subject designs, one a line-drawing and the other a color design adapted when the two are superposed to register so that they complement each other, next preparing a set of printing color-plates from the color design by the usual photomechanical process and conjunc- 85 tive use of color-filters and screen, and also preparing a printing key-plate from the line-drawing by photomechanical reproduction, the exposure of the photographic plate being made through a filter having the same coefficient of refraction as the filters used for producing the color-plates, then making the final print by successively printing, in superposed relation, the several colors from the corresponding color-plates and finally finish- 90 ing the print with the impression from the key-plate.

4. The improvement in the art of making multicolor prints which consists in first making an outline-drawing, the lines of which are 100 in a color adapted to reproduce sharply upon a photographic negative, next photomechanically preparing a printing-plate adapted to reproduce said line-drawing, next preparing two prints from said printing-plate, the lines 105 of one of which appear in a color adapted to reproduce sharply upon a photographic negative, filling in the other of said prints with a color design so that the two form a pair of complementary subject designs, next preparing a printing key-plate from the line-drawing and a set of printing color-plates from the color design, both by photomechanical reproduction, and then making the final print by successively printing, in superposed 110 relation, the several colors of the corresponding color-plates, and finishing with the impression from the key-plate in a strong color. 115
